UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

GUIDE MEANS FOR WARPERS AND SIMILAR MACHINES.

Application filed May 21, 1923. Serial No. 640,430.

To all whom it may concern:

Be it known that I, ALONZO E. RHOADES, a citizen of the United States, and resident of Hopedale, county of Worcester, and State 5 of Massachusetts, have invented an Improvement in Guide Means for Warpers and Similar Machines, of which the following description, in connection with the accompanying drawing, is a specification, like 10 characters on the drawing representing like parts.

This invention relates to yarn winding machines wherein the yarn is wound upon a core in a cylindrical mass by means of a 15 driven winding drum mounted in parallelism with the core and acting by peripheral engagement with the yarn mass on the core to effect the winding operation.

The invention in its preferred form is 20 particularly designed for a warper wherein the yarn is wound upon a warp beam comprising a core, heads in the form of disks at each end and journals, but it is equally applicable in its broader aspects to any form 25 of yarn winding machine of this type wherein it is desired or necessary to maintain the longitudinal position of the yarn receiver in a relatively fixed position with respect to the frame and the winding drum.

30 The object of the invention is primarily to provide means in combination with the elements of the machine involved which act to prevent longitudinal movement of the yarn receiver relatively to the drum during the 35 winding operation or which act to maintain the yarn receiver during the winding operation in fixed longitudinal position.

In this type of machine there is necessarily a relative bodily transverse movement 40 between the core on which the yarn is wound and the winding drum in order to effect the winding operation and in the warper one of these elements, usually the beam, is journalled in arms hinged or movably secured to 45 the frame so as to allow the beam to swing or move bodily transversely toward and from the drum. The winding drum usually comprises a relatively thin cylindrical iron shell open at the ends and if the longitudinal 50 position of the beam is not maintained fixed the longitudinal movement of the beam due to the longitudinal shifting of its bearings or the yield of the supporting arms allows the ends of the shell of the winding 55 drum to engage and grind against the heads

of the warp beam often injuring or damaging the winding drum. Furthermore, this grinding action often so reduces the length of the winding drum as to prevent the proper pressure being applied to the ends of the 60 cylindrical yarn mass wound on the beam. This is highly undesirable as it results in "soft" yarn at the ends of the mass and unequal tension throughout the yarn mass.

With this invention the warp beam or 65 other yarn receiver is accurately maintained in a fixed longitudinal position so that during the winding operation and during the transverse movement of the beam or yarn receiver there is no danger of the heads of 70 the warp beam engaging the winding drum consequently the winding drum is uninjured and its length maintained. The pressure on the yarn mass is kept uniform throughout 75 and accuracy in the placing of the yarn upon the beam or yarn receiver is insured.

The present invention in its broader aspects is subsidiary to the invention set forth in my application filed concurrently herewith, Serial No. 640,429. In the present invention, in its preferred form, a follower and guide are provided, one secured to the movable element, usually the yarn receiver, and the other to the frame, and these co-operate to prevent the undesirable longitudinal 80 movement during the relative transverse movement between the yarn receiver and winding drum.

These and other objects and features of the invention will more fully appear from 85 the accompanying description and drawings and will be particularly pointed out in the claims.

In the drawings:

Fig. 1 is a side elevation of a portion of an 90 ordinary type of warper with only those parts shown which are necessary for a disclosure of the present invention;

Fig. 2 is a plan view of the construction 95 shown in Fig. 1 with the central portion of the mechanism broken away;

Fig. 3 is a detail of the bottom plan view 100 of the follower construction shown in Fig. 5;

Fig. 4 is a view in transverse cross section taken on the line 4—4 of Fig. 5;

Fig. 5 is an elevation looking toward the 105 left of Fig. 3.

The invention in a preferred form is herein shown embodied in an ordinary and familiar type of warper and, as the invention 110

is only concerned with a specific feature of the operation of the warper, it is only necessary to illustrate and describe those features of the warper directly concerned with the 5 invention.

This type of warper comprises a frame including vertical side members 1 and 2 which support the various shafts and other parts of the warper. The yarn receiver, 10 which in this case is a warp beam, comprises a cylindrical core 3 on which the yarn mass is wound, journals 4 projecting at each end of the core, and generally flat or disk-shaped heads 5. These heads on the interior 15 positively facing surfaces are flat and on the exterior surfaces are generally ribbed and braced as illustrated. The journals of the warp beam are usually mounted in bearings 6 formed in the ends of arms 7 movably 20 mounted on the frame. These arms allow the warp beam to move transversely or swing toward and from the frame. The warp beam is a very heavy structure as the heads are made of cast iron or steel and the 25 heavy mass of yarn wound thereon greatly increases the total weight supported in the journal bearings.

The winding drum usually comprises an iron cylinder 8 having a central shaft presenting the journals 9 mounted in bearings 30 on the frame. The drum shaft extends parallel to the beam shaft and the drum is rotated in the usual manner. The periphery of the drum rests against the yarn mass on 35 the core of the beam and thus acts to effect the winding operation, the beam swinging or moving transversely away from the drum as the operation proceeds. While the relative transverse movement which takes place 40 between the winding drum and the yarn receiver is in the illustrated case secured by the transverse bodily movement of the yarn receiver, it will be understood that the present invention in its broader aspects is in 45 dependent of the manner in which this transverse relative movement is secured. Furthermore, while the yarn receiver is illustrated as a warp beam having heads, the particular form of the yarn receiver is not im- 50 portant in the broader aspects of the invention.

In the preferred construction illustrated the fixed longitudinal position of the yarn receiver is secured, and thus longitudinal 55 movement with respect to the frame and the winding drum is prevented by a follower and guide construction. One of these elements is secured to the frame and the other forms a part of, or is secured to, the trans- 60 versely movable element, which in the case illustrated is the warp beam. The follower and guide co-operate during the trans- 65 verse movement of the movable element, such as the warp beam, which occurs during the winding operation, and insure that the longi-

tudinal position of the movable element is maintained and consequently any relative longitudinal movement between that element and the frame and the co-operating element, such as the winding drum, is prevented. 70

In the preferred construction illustrated the follower is in the form of a shoe secured to the journal of the warp beam and the guide is in the form of a track standing at right angles to the axis of the warp beam but 75 curved on its face to co-operate with the path of travel of the axis of the warp beam during its transverse movement.

The guide 10 is in the form of a flat plate extending in a plane at right angles to the axis of the warp beam and having its face 80 curved to correspond substantially to the path of movement of the axis of the warp beam during the winding operation. This plate 10 is secured to a socket 12 which in turn is rigidly secured by a set screw 13 to an arm or shaft 14 rigidly secured by the set screw 15 in a socket 16 forming a part of a bracket 17 bolted at 18 to the frame. This construction enables the position of the 85 guide plate to be accurately adjusted.

The follower shoe, in the preferred construction illustrated, is mounted on the warp beam journaled 4 and, as the follower co-acts best with the guide when non-rotatable, 90 this follower provides a construction by which it may still be mounted upon the rotatable journal 4 and yet not rotate with respect to the guide. A sleeve 19 is provided to fit over the journal 4 and this sleeve has 95 at the outer end a comparatively large annular head 20, and at the inner end a comparatively small annular head 21. There is consequently presented between these annular heads an external annular recess on the 100 sleeve. The sleeve is rigidly secured in proper position on the journal 4 by a set screw 22 threaded through the head 20 and abutting the journal. The follower shoe is 105 mounted in this recess and preferably comprises a shoe base 23 and a cap 24 having flat co-operating surfaces and bolted together by the set screws 25. The line of division between the base and cap is diametrically of 110 the journal 4, and these parts are constructed, when bolted together, to fit the annular recess in the sleeve 19 so that they may 115 rotate with respect to the sleeve, but be prevented from longitudinal movement with respect to the sleeve by the annular heads 20 and 21. At their outer ends the shoe base and cap present an annular rim 26 concentric with but spaced from the sleeve head 20 thus providing an annular recess between 120 the head 20 and the rim 26 to guard the set screw 22 which rotates with the journal of 125 the warp beam.

The follower shoe, preferably on the base member 23, is provided with guiding lugs to fit and coact with the guide 10. In the 130

form shown the lugs 27, which are quite widely separated, present surfaces which fit against and slide upon the face 11 of the guide 10. Intermediate of the lugs 27 are a pair of lugs 28 spaced to form a recess 29 of the same width as the guide 10. These lugs 28 extend past the sides of the guide 10.

Thus it will be seen that longitudinal movement of the shoe, and consequently of the sleeve 20, and consequently of the warp beam, is prevented with respect to the guide 10, and consequently with respect to the frame and winding drum 8, at all positions of the warp beam.

The follower shoe is readily secured in place by slipping the sleeve 19 over the journal 4 and locking up the set screw 22 at the proper point. The shape of the guide 20 and the co-operating lugs on the shoe will depend of course on the path of travel of the movable element, such as the warp beam. The shoe and guide are adjusted so as to provide the proper positioning engagement therebetween without binding and slight play may be allowed so long as the positioning engagement is such as to prevent the beam heads from contacting with the winding drum during the winding operation. As the drum is rotated, the beam slowly swings or moves away from the drum and its longitudinal position is maintained with a minimum amount of friction.

It will thus be seen that the invention 35 obviates the difficulties heretofore encountered and insures the accurate longitudinal position of the beam or yarn receiver with respect to the winding drum and the frame at all times.

Having thus described the invention, what is claimed as new and desired to be secured by Letters Patent, is:

1. A yarn winding machine comprising a frame, a yarn receiver having a core, a winding drum in parallelism with the core and acting by peripheral engagement with the yarn mass on the core to effect the winding operation, means to permit relative transverse movement of the core and drum to permit transverse separation of the core and drum as the winding operation proceeds, and a follower and guide, one secured to the movable element and the other to the frame and co-operating to prevent relative longitudinal movement of the said element with respect to the frame during its transverse movement.

2. A yarn winding machine comprising a frame, a pair of aligned bearings supported and transversely movable on the frame, a yarn receiver having a core and journals mounted in said bearings, a winding drum mounted on the frame in parallelism with the core and acting by peripheral engagement with the yarn mass on the core to

effect the winding operation, a guide mounted in rigid position on the frame, and a follower mounted on the yarn receiver and secured against longitudinal movement with respect thereto and co-acting with the guide 70 during the transverse movement of the yarn receiver to prevent longitudinal movement of the yarn receiver with respect to the frame during its transverse movement.

3. A yarn winding machine having the 75 construction defined in claim 2 in which the guide is in the form of a flat plate mounted at right angles to the axis of the yarn receiver and in which the follower is in the form of a shoe provided with lugs engaging 80 the face and sides of the guide.

4. A follower shoe comprising a sleeve to fit over a journalled shaft and having heads at its ends presenting therebetween an external annular recess, means on the sleeve to secure it rigidly to the shaft, a shoe base and cap fitting said recess whereby the shoe is permitted to rotate on the sleeve and prevented from longitudinal movement on the sleeve, means for removably securing together the shoe base and cap, and guiding lugs on the shoe to fit a guide extending at right angles to the shaft and acting to allow the shoe to follow the guide but to prevent movement of the shoe laterally of the guide.

5. A follower shoe having the construction defined in claim 4 in which the shoe base and cap present at one end an annular rim concentric with but spaced from the corresponding sleeve head, thus forming an annular recess between the said sleeve head and annular rim and in which the means for securing the sleeve to the shaft comprises a set screw in said head projecting beyond the periphery of the head and into the annular recess formed between the head and the concentric annular rim.

6. A yarn winding machine comprising a frame, a yarn receiver having a core, a winding drum in parallelism with the core and acting by peripheral engagement with the yarn mass on the core to effect the winding operation, means to permit transverse movement of the yarn receiver with respect to the drum as the winding operation proceeds, and a guide supported rigidly from the frame at right angles to the axis of the yarn receiver acting to guide the yarn receiver in its transverse movement during the winding operation and prevent longitudinal movement thereof.

7. A winding machine comprising the construction defined in claim 6 together with means for effecting a relative bodily longitudinal adjustment between the guide and the yarn receiver.

In testimony whereof, I have signed my name to this specification.

ALONZO E. RHOADES.
